CLAIM

The ornamental design for a loudspeaker, as shown and described.

DESCRIPTION

FIG. 1 is a top perspective view of a loudspeaker of embodiment one, showing our new design;

FIG. 2 is a front elevational view thereof;

FIG. 3 is a rear elevational view thereof;

FIG. 4 is a side elevational view thereof;

FIG. 5 is an opposite side elevational thereof;

FIG. 6 is a top plan view thereof;

FIG. 7 is a bottom plan view thereof;

FIG. 8 is a top perspective view of a loudspeaker of embodiment two, showing our new design, shown in enlarged scale;

FIG. 9 is a front elevational view thereof;

FIG. 10 is a rear elevational view thereof;

FIG. 11 is a side elevational view thereof;

FIG. 12 is an opposite side elevational view thereof;

FIG. 13 is a top plan view thereof;

FIG. 14 is a bottom plan view thereof;

FIG. 15 is a top perspective view of a loudspeaker of embodiment three, showing our new design, shown in enlarged scale;

FIG. 16 is a front elevational view thereof;

FIG. 17 is a rear elevational view thereof;

FIG. 18 is a side elevational view thereof;

FIG. 19 is an opposite side elevational view thereof;

FIG. 20 is a top plan view thereof; and,

FIG. 21 is a bottom plan view thereof.

The broken lines in the figures illustrate the portions of the design that form no part of the claimed design.

1 Claim, 18 Drawing Sheets
